UNITED STATES PATENT OFFICE.

JOHN A. SOWELL, OF STOCKTON, CALIFORNIA, ASSIGNOR OF ONE-HALF TO ERNEST E. SOWELL, OF SACRAMENTO, CALIFORNIA.

AEROPLANE.

1,331,593.

Specification of Letters Patent. Patented Feb. 24, 1920.

Application filed December 3, 1918. Serial No. 265,098.

To all whom it may concern:

Be it known that I, JOHN A. SOWELL, a citizen of the United States of America, residing at Stockton, in the county of San Joaquin, State of California, have invented certain new and useful Improvements in Aeroplanes; and I do declare the following to be a clear, full, and exact description of the same, reference being had to the accompanying drawings, and to the characters of reference marked thereon, which form a part of this application.

This invention relates to improvements in aeroplanes; the principal object being to produce an aeroplane which will control the air instead of the machine being controlled by the air.

A second object has been to so construct the aeroplane that the air currents or air pressure against opposite sides of the machine will be equalized and the aeroplane will thereby have great stability. In this respect, the aeroplane is so constructed that the air pressures from opposite sides on meeting or coming together are forced upward, thus being utilized to help raise the machine.

By means of a construction hereinafter described the resistance at the forward end is overcome and a vacuum is formed at that end, whereby the same has a tendency to rise and the upper parts are stabilized.

I have also provided a means whereby the resistance of the air is distributed equally over all parts of the machine, thereby giving the same lateral stability and assuring positive balance.

By means of other construction, I am enabled to shut off the driving power and remain stationary in the air or ascend and descend at will thereby, and in a vertical plane.

I have also constructed my aeroplane so that the center of gravity will at all times be on the same vertical line as the center of pressure.

As a further object, I have produced a device which is simple of construction and operation and yet exceedingly effective for the purpose for which it is designed.

These objects, I accomplish by means of such structure and relative arrangement of the parts as will fully appear by a perusal of the following specification and claims.

On the drawings, similar characters of ref-

erence indicate corresponding parts in the several views.

Figure 1 is a perspective elevation, depicting the aeroplane in flight.

Fig. 2 is a fragmentary cross section taken on a line 2—2 of Fig. 1.

Fig. 3 is a top plan view of the fuselage, and lower wing plane.

Fig. 4 is a fragmentary cross sectional view of an elevating and depressing mechanism, taken on a line 4—4 of Fig. 3.

Fig. 5 is a fragmentary view, partly broken away of a steering mechanism.

Referring now more particularly to the numerals of reference on the drawings, the numeral 1 designates the fuselage, which is of cigar-shape form, but larger at the rear than the forward end, on both sides of which and positioned on a horizontal line halfway up the sides thereof are lower wings 2. These wings are flat, or, in other words, lie in one horizontal plane, and are provided with large fore and aft openings 3 for a purpose as will appear.

Projecting upwardly from these planes or wings are suitable struts 4, to which are secured upper wings 5. These wings overhang the planes 2 along the sides thereof, are substantially parallel thereto, and are warped convexly in a fore and aft direction, the edges thereof near the longitudinal center of the aeroplane being suitably spaced apart and bent upward at an angle for a certain distance as shown at 6.

These edges and the space between the wings is covered by a tube or tunnel 7 of substantially cylindrical cross section, but has a peak 8 arising centrally therefrom and extending longitudinally thereof.

The lower edges of this tube terminate somewhat short of the wings 6, leaving a longitudinal opening 9 therebetween on both sides.

A cylindrical tank 10 may be positioned in the tube; so as to keep the fuel as far from the engine as possible.

A corkscrew propeller 11 is positioned in the forward end of the tube, this propeller projecting from the tube for the greater part of its length and terminating in a point, the after portion thereof being of nearly as great a diameter as the tube itself. This propeller is driven by any suitable means such as a chain drive 12 from a power plant

- 12^a suitably positioned in the forward end of the fuselage. Suitable guy or truss wires 13 are positioned where necessary to give the machine the necessary rigidity.
- 5 Positioned at the forward end of the fuselage is a three-bladed rudder 14, mounted for lateral and vertical movement by any suitable type of bearing as for instance, that depicted at 15, this bearing being covered 10 by a hood 16 so that the air will be deflected therefrom. This rudder may be operated directly by a handle 17, or it may be controlled by a cable mechanism such as is indicated at 18.
- 15 At the rear of the fuselage is the driving propeller 17, driven by a power plant suitably positioned, but preferably an independent plant from the one driving the forward corkscrew propeller.
- 20 Positioned in the orifices 3 are wide bladed propellers 20, these being mounted in a horizontal plane and pivotally mounted on shafts 21 which span these orifices transversely. These propellers are driven through 25 suitable gearing 22 arranged about the intersecting point of the vertical propeller shaft and the transverse shaft, the transverse shaft being in driving relation with the power plant 12^a. A suitable casing 23 covers the gearing 22 on each propeller, which casing is adapted to turn on the shaft 21. An arm 24 projects upward from each of the casings 23, and each pair is operatively connected to a lever 25 suitably positioned within reach of the aviator, whereby the propellers 20 may be swung on the shafts 21 to alter the angle of the propellers with the planes 2 in a longitudinal direction.
- 25 Shields 26 are positioned under and partly around the orifices 3, whereby the air thrown against them will be deflected and thrown down into the path of the air current caused by the turning of the propeller.
- 30 The principles of operation and construction are as follows:—
- 35 The forward cork screw propeller 11 being positioned in the center and forward end of the tube breaks the atmospheric pressure caused by the advancing motion of the aero- 40 plane and forms a vacuum or trough at this point whereby the machine has a tendency to rise at the forward end. This also eases up the strain on the rear driving propeller 19 and stabilizes the upper portions of the 45 aeroplane.
- 40 The fuselage 1 being positioned one half below the lower wings 2, this has its greatest weight under these wings, thus giving the aeroplane a very low center of gravity.
- 45 The horizontal propellers 20 positioned in the lower wings 2 being controllable as to their fore and aft angle with the planes or wings 2, provide a means for giving perfect balance to the aeroplane, taking the 50 place of the usual ailerons, and also form a 55 means for lifting the machine directly upward against the lower pressure of air. The action of these propellers holds the aeroplane in a channel or trough, causing the resistance of the air to strike against all parts 60 equally, giving the aeroplane great lateral stability. Longitudinal stability is gained as described by the aileron action of the propellers 20 and by the corkscrew propeller 11. Also, the propellers 20 exert their force 65 against the pressure of the air beneath the aeroplane, and by holding these propellers all on a horizontal plane the machine may be held stationary in the air, and prevented from falling, by merely cutting off the power 70 from the driving propeller 19, and rotating the propellers 20 at a speed sufficient to just counteract the force of gravity, or they may be speeded up so as to cause the aeroplane to 75 rise directly from the ground in a vertical path.
- 80 Thus it will be seen that I have made great improvements over the type of aeroplane now used, in that I have overcome head resistance, am not dependent on high speed for air staying qualities, I have gained great stability, both longitudinal and lateral, and am enabled to stand indefinitely in one position in the air and can ascend or descend 85 in a vertical plane.
- 90 While this specification sets forth in detail the present and preferred construction of the device, still in practice, such deviations from such detail may be resorted to as do not form a departure from the spirit of 95 the invention as defined by the appended claims.
- 95 Having thus described my invention, what I claim as new and useful and desire to secure by Letters Patent is:—
1. An aeroplane comprising in combination with a fuselage and propulsive means therefor, lower planes secured thereto, upper planes spaced therefrom and an open ended longitudinal tube positioned centrally 100 between the upper planes, the tube being provided with a peak lengthwise thereof and the upper planes being convexly warped transversely whereby the air striking the outside of said wings will be thrown against 105 the central tube to stabilize the aeroplane.
2. An aeroplane comprising a fuselage, flat planes extending lengthwise and on each side thereof, a driving propeller on the rear end of the fuselage, horizontally positioned 110 lift propellers mounted on said flat planes in orifices provided therein, upper planes spaced from the lower planes, and parallel thereto, the upper planes being convexly warped longitudinally, and the inner edges 115 thereof being angled upwardly and spaced apart, and a tube extending lengthwise of said upper planes and covering said angled edges, the tube having a slot on each side thereof opening onto said angled edges, 120
- 125
- 130

whereby the air pressure on the outer surface of the upper planes will pass through the slots and be diverted by the angled edges of the upper planes and be thrown upward 5 against the inner walls of the tube.

3. An aeroplane comprising a fuselage, flat planes extending lengthwise and on each side thereof, a driving propeller on the rear end of the fuselage, horizontally positioned 10 lift propellers mounted on said flat planes in orifices provided therein, upper planes spaced from the lower planes, and parallel thereto, the upper planes being convexly

warped longitudinally, an open ended tube extending lengthwise and central of said 15 upper planes, and a corkscrew propeller positioned in the forward end of the tube and projecting therefrom, whereby the air pressure caused by the forward motion of the aeroplane is attacked and controlled. 20

In testimony whereof I affix my signature in presence of two witnesses.

JOHN A. SOWELL.
